UNITED STATES PATENT OFFICE

LEONHARD KOCH, OF OELSNITZ IN VOGTLAND, GERMANY

WEFT PILE CARPET

Application filed October 7, 1930, Serial No. 486,890, and in Germany October 30, 1929.

This invention relates to the production of a novel chenille stock for use in the manufacture of weft pile carpets, and to the manufacture from such chenille stock of an improved weft pile carpet without a woven backing. It is a primary object of the present invention to produce a weft pile carpet without a woven backing, while obtaining softness and depth of plush, softness or pliability of the carpet fabric as a whole, a clear-cut surface effect in the design, and the appearance of a connected design on the back to such a high degree as to approximate to the properties of valuable oriental carpets.

Previous attempts to make Axminster carpets without a woven backing have generally been limited to the use of a twine warp to permit the loops of the tufted pile to appear at the back of the carpet. The tufts of the chenille were in such case however too firmly bound around the stuffing warp and the twine warp was too clearly visible. The appearance of the design on the back of the carpet therefore lacked good continuity. Moreover the very regular structure of the chenille spoilt the clear-cut effect of the design on the surface by producing stripes, that is to say, it was possible to distinguish one chenille shot from another. The softness and depth of the plush and the softness or pliability of the carpet fabric as a whole were also spoilt by the difference in the warps employed. A strong taut thread, i. e. a stretched thread in the finished fabric was worked in together with two weaker threads so that the latter bound the chenille shots below, but bound the majority of the stiffening shots above the taut thread. These stiffening shots which were above the taut thread and which consequently lay over the chenille stuffing warp, in conjunction with the strong taut threads, made the carpet fabric stiff and shortened the free length of the tufts, because they pressed the tufts against one another again above the stuffing warps. The softness and depth of the plush was thus detrimentally affected.

It has also been proposed to interweave the chenille solely with a double twine ground warp which binds the stiffening shots in pairs

with a plain one and one weave. The stiffness of the carpet is however reduced by this method and it does not carry any other advantages with it, owing to the chenille being too firm and of too uniform a structure.

The present invention consists in the production of a novel chenille stock, and in interweaving it in a novel manner with a double ground warp, in such a manner that the two cooperate together to fulfil the object of the present invention.

According to the present invention the chenille stock is produced by drawing the pile weft freely around a plurality of stuffing warp threads alternately to right and left by the use of a single crossed warp between the stuffing warp and binding warps on both sides of the stuffing warp. The chenille stock so produced is bound as weft in alternation with stiffening shots solely by the use of a double ground warp which passes alternately over the binding warps and under the stuffing warp of the chenille, the double ground warp binding the stiffening shots in pairs with a plain one and one weave.

An example of the manner in which the invention can be carried out is illustrated in the accompanying drawings whereon:

Fig. 1 is a plan view of the chenille weave and Figs. 2 and 3 are sectional views of the chenille stock, assumed to be cut between two neighbouring tufts.

Fig. 4 is a plan view showing the carpet weave and Figs. 5 and 6 are cross-sectional views in the direction of the carpet warp and chenille weft respectively.

As illustrated in Fig. 1, the pile wefts 1 of the chenille stock are in themselves quite loose from the three stuffing warps 2 and are merely drawn around the stuffing warps by a crossed warp thread 3, which alternately engages the right and left hand portions of successive pile shots. At distances x and y from the crossed warp 3, the pile shots are bound to crossed warp thread 6, at both sides of the stuffing warp, by the usual twine binding warp 4 and 5.

As the crossed warp 3 always passes around first one limb of a tuft and then the other limb of the next tuft, the limbs of the

tufts which are not caught by the crossed warp 3, must be drawn with it by the aid of the twine binding warps 4, 5 and 6 at the same side of the stuffing warps as the free limb of 5 the tuft. The tuft limbs directly caught by the crossed thread 3 are therefore unable to freely follow it. On the contrary the twine binding warps 4, 5 and 6 act as a resistance to it created by the resistance of the neighbouring 10 tuft limb. Those tuft limbs which are drawn inwards directly over the stuffing warp by the crossed warp 3 will therefore, at their free ends, bend outwards slightly about the twine binding warps and above the 15 crossed warp 3 as a resistance and fulcrum. The neighbouring tuft limbs drawn inwards only at a single point by the twine binding warps can freely follow this pull and therefore take a bend inwards at one side. This 20 is shown in a somewhat exaggerated manner in Figs. 2 and 3. In Fig. 2 the right limb of the tuft is directly caught by the crossed warp 3 and its free end is bent outwards above the twine binding warps. The left 25 limb caught only by the twine binding warps is only drawn inwards and therefore follows the same direction as the right limb. In Fig. 3 the conditions are just the reverse; both limbs of the tuft bend towards the left. 30 This chenille stock thus exhibits adjacent tuft limbs directed alternately inwards and outwards. If such united chenille weft shots are pressed together when weaving the 35 carpet, the tufts of one stock weft which are bent in one direction can be caused to fit between the oppositely bent tufts in the next stock weft, so that the tufts intermingle and the line of distinction between the shots is thus effaced and a true stripeless surface effect 40 is obtained in the design.

As shown in Figs. 4, 5 and 6 this chenille stock is now bound in with two stiffening weft threads 8 by a double twine ground warp 7, which passes alternately over the 45 twine binding warps 4, 5 and 6, see Figs. 5 and 6, and under the stuffing warps 2, the ground warp 7 binding the stiffening shots 8 in pairs with a plain one and one weave. The ground warp threads being similar in 50 themselves and consisting of fine threads, they cooperate in a particularly advantageous manner with the chenille stock. In the first place this ground warp is fine enough to pass through the loops of the tufts until 55 it rests against the stuffing warps, and secondly the loops of the tufts are loose enough to permit the ground warp to pass through it. The complete absence of any binding of the tuft loops to the stuffing warp over the 60 distance y of Fig. 1, and the fact that this distance lies alternately to right and left, prevents the design formed on the back by the tuft loops from being too regularly interrupted, and also permits the formation of 65 the tuft loops to be looser, thereby permitting

a more connected design to appear on the back of the carpet.

The fact that the twine ground warp passes over the binding warps 4, 5 and 6 and under the stuffing warps of the chenille, acts to 70 press them both together and thus brings them closer towards each other. This allows the tuft loops to hang downwards in a loose condition, the ground warp penetrates the tuft loops with more certainty, it becomes 75 concealed within them, and makes the tuft loops softer. The pressure of the twine ground warp against the binding warps of the chenille also strengthens the action of the crossed warp on the inclination of the 80 tufts in alternately opposed directions. This ground warp therefore improves the clear-cut surface effect of the carpet design on the face.

As the twine ground warps are all of the 85 same material, this causes the stiffening shots to be bound in at about the same level as the stuffing warp of the chenille. This is also assisted by the three stuffing warp threads, which lie entirely loose, because according 90 to whether at any place a lateral or a vertical pressure predominates, the stuffing warp threads can lie either closer above one another, as in Fig. 2, or somewhat nearer together, as in Fig. 3, that is to say, they can 95 themselves yield without forcing the stiffening shots to move upwards or downwards. The stiffening shots being positioned at the same level as the stuffing warps of the chenille 100 substantially improves the softness of the carpet, as well as the depth and softness of the plush, because this is not hemmed in above the stuffing warp by any stiffening shots.

I claim:

1. A weft pile carpet fabric comprising stock wefts cut from chenille made from pile wefts, sets of stuffing warps, a crossed warp twined from side to side of each set of stuffing warps with a pile weft inserted at every twist, and binder threads uniting the pile wefts between the sets of stuffing warps, stiffening wefts alternating with the stock wefts, and ground warps interwoven with the stock wefts and stiffening wefts, said stock wefts being assembled so that the tufts of one stock weft which are bent in one direction fit between the tufts in the next stock weft which are bent in the opposite direction.

2. A weft pile carpet fabric comprising stock wefts exhibiting tufts bent alternately to right and left and cut from chenille made from pile wefts, sets of stuffing warps, a crossed warp twined from side to side of each set of stuffing warps with a pile weft inserted at every twist, and binder threads uniting the pile wefts between the sets of stuffing warps, stiffening wefts alternating with the stock wefts, and ground warps interwoven with the stock wefts and stiffening wefts,

said stock wefts being assembled so that the tufts of one stock weft which are bent in one direction fit between the tufts bent in the other direction in the next stock weft, said 5 crossed warp being tensioned to pull the pile wefts around the stuffing warps and force the ends of the pile wefts into staggered relation.

3. A weft pile carpet fabric comprising 10 stiffening wefts arranged in pairs, a stock weft between each pair of stiffening wefts, said stock wefts exhibiting tufts bent alternately to right and left and cuts from chenille made from pile wefts, sets of stuffing warps, 15 a crossed warp twined across each set of stuffing warps with a pile weft inserted at each twist, and binder threads uniting the pile wefts between the sets of stuffing warps, and ground warps interwoven with the stock 20 wefts and stiffening wefts, said ground warps passing over the binder threads of alternate stock wefts, under alternate pairs of stiffening wefts and under the stuffing warps of the intermediate stock wefts, and said 25 ground warps being arranged in pairs one under and one over each stock weft and its adjacent pair of stiffening wefts, the stock wefts when assembled having the tufts of one stock weft bent in one direction and fitting 30 between tufts in the next stock weft which are bent in an opposite direction.

Signed at Oelsnitz i. V. Saxony, Germany,
